UNITED STATES PATENT OFFICE.

DANIEL CHASE, OF NEW YORK, N. Y., ASSIGNOR TO THE STRONG MACHINERY & SUPPLY CO.,
OF NEW YORK, N. Y., A CORPORATION OF NEW YORK.

BELT-COUPING.

No. 901,952.

Specification of Letters Patent.

Patented Oct. 27, 1908.

Application filed November 26, 1907. Serial No. 403,939.

To all whom it may concern:

Be it known that I, DANIEL CHASE, a citizen of the United States, residing at New York city, in the county of Kings and State of New York, have invented certain new and useful Improvements in Belt-Couplers; and I do hereby declare the following to be a full, clear, and exact description of the invention, such as will enable others skilled in the art 10 to which it appertains to make and use the same.

This invention relates to improvements in belt couplers and comprises improved pivotally mounted members hinged together for forming a comparatively light and yet very strong flexible connection.

The invention further comprises the provision of a coupler formed from material stamped from sheet metal and arranged to be 20 bent for forming receiving members for accommodating a connecting pintle or shaft.

The object in view is provision of a coupler that is flexible and yet so formed as to be very strong and of comparatively light 25 weight.

With these and other objects in view the invention comprises certain novel constructions, combinations, and arrangement of parts that will be hereinafter more fully described and claimed.

In the accompanying drawing: Figure 1 is a perspective view of my improved coupler secured to a belt. Fig. 2 is a plan view of my improved coupler. Fig. 3 is a section of Fig. 2 on line 3—3. Fig. 4 is a plan view of a blank forming half or one part of my improved coupler.

In constructing a coupler according to the present invention I have designed to make 40 the same preferably of strong steel and yet so arranged as to be comparatively light in weight.

In constructing the parts of the coupler the same are stamped from sheet metal 45 and only require bending for forming an opening for the reception of a shaft or pintle before being completed, ready for use.

Referring more particularly to the drawing 1 indicates one-half of the coupler and 2 the remaining half secured together by a 50 pintle 3. The members 1 and 2 are made identical so as to fit together when completed as seen in Figs. 1 and 2. In constructing a coupler the members 1 and 2 are stamped 55 the same from sheet metal and form a blank

as seen in Fig. 4. In stamping the metal, openings 4 are provided and also bars or strips 5. These are of considerable length so as to form an opening through which a pintle 3 is designed to pass when the end 6 60 of the blank is folded over against end 7. The holes or apertures 8 in the end 6 are designed to be of a larger size than holes or apertures 9 in the end 7 so that all the holes or apertures may be punched at one 65 time before turning or forming the blank into a completed coupler.

The forming of holes or apertures 8 larger than the remaining apertures permits a leeway when turning the blank so that if the 70 holes or apertures do not exactly register, the size of apertures 8 will permit rivets or securing means 10 to pass through both apertures without difficulty. This obviates the necessity of turning over the end 6 against the end 7 before punching, and consequently 75 saves the necessity of punching holes through two thicknesses of metal. Projecting from end 7 is a lug or extension 11 formed with apertures 12 for accommodating securing 80 means as rivets 13 which are designed to be passed through apertures 12 and through the belt to assist rivets 10 in holding the coupler in position.

In assembling the coupler two blanks as 85 shown in Fig. 4 are taken and the end 6 of each blank turned over so as to be in the position shown in Fig. 3. It will be observed that the end 6 does not extend over to extension 11 but extends simply far enough 90 for holes or apertures 8 to register with apertures 9. This will save material and also permit the couplers to be made considerably lighter with equal strength. After the two blanks have been folded or turned the strips 95 or bars 5 in one of the blanks is inserted into the apertures or slots 4 of the other blank and pintle 3 passes through the two blanks thus uniting the same and presenting a complete coupler as seen in Fig. 2. The securing 100 means or rivets 10 and 13 are designed to be passed through the belt as seen in Figs. 1 and 3 for firmly holding the coupler in position. When two of the blanks have been secured together by pintle 3 as just set forth a hinged portion or extension 14 is provided. The hinged portion 14 in securing the coupler in place is designed to be placed between the ends of the belt as seen in Fig. 3. It 105 will also be observed that in placing the 110

coupler in position on the belt the lugs or extensions 11 are bent so as to be in the same plane as the end 6. In this way the coupler contacts with the belt substantially from pintle 3 to the extreme end of the coupler.

In constructing a coupler according to the present invention the openings 4 are designed to be stamped out and to extend as 10 near the apertures 8 and 9 as possible without weakening the coupler. By cutting out the metal between openings 12 and by forming lugs or member 11 as an extension considerable material is dispensed with, and 15 thus the device is lightened. From this it will be evident that all the superfluous metal is cut away and only sufficient metal remains to form a strong and efficient coupler.

What I claim is:

20 1. In a belt coupler, a plurality of pivotally mounted plates, each of said plates being formed from a single piece of material and folded upon itself to form a pintle

receiving portion and being again deflected until its inner edge is in a plane with the 25 outer edge of the folded portion, and a pintle passing through said plates for pivotally securing the same together.

2. In a belt coupler, a plurality of plates, means for pivotally securing same together 30 and means for securing said plates to said belt, each of said plates being stamped from a single piece of sheet metal and formed with elongated bars designed to be bent for receiving said pintle and an extension 35 formed on one edge of each of said plates bent for taking a position in the same plane as the end of that portion of the plate that is bent over for forming a pintle receiving portion.

40 In testimony whereof I affix my signature in presence of two witnesses.

DANIEL CHASE.
